UNITED STATES PATENT OFFICE

162,109

AUTOMOBILE GASOLINE DOOR GUARD

Perry E. Allen, Detroit, Mich.

Application September 7, 1950, Serial No. 12,098

Term of patent 7 years

(Cl. D14—6)

To all whom it may concern:

Be it known that I, Perry E. Allen, a citizen of the United States, residing in Detroit, county of Wayne, and State of Michigan, have invented a new, original, and ornamental Design for an Automobile Gasoline Door Guard, of which the following is a specification, reference being made to the accompanying drawing, in which drawing:

Fig. 1 is a plan view of an automobile gasoline door guard embodying my new design.

Fig. 2 is a side elevational view thereof.

Fig. 3 is a section taken on the line 3—3 of Fig. 2.

Fig. 4 is a section taken on the line 4—4 of Fig. 2.

I claim:

The ornamental design for an automobile gasoline door guard, as shown.

PERRY E. ALLEN.
